UNITED STATES PATENT OFFICE.

CHARLES J. CARTER, OF KANSAS CITY, MISSOURI

NAIL SET.

1,412,507.

Specification of Letters Patent. Patented Apr. 11, 1922.

Application filed June 4, 1921. Serial No. 474,890.

To all whom it may concern:

Be it known that I, CHARLES J. CARTER, a citizen of the United States, residing at Kansas City, in the county of Jackson and State of Missouri, have invented certain new and useful Improvements in Nail Sets; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to nail sets for flooring and one of the objects is to provide means whereby nails may be conveniently set in the flooring and the like so that the heads will be countersunk, the nail set being provided with a gauge or nail finder to expedite the operation of laying the floor.

A novel construction of the nail set will be apparent by reference to the following description in connection with the accompanying drawings, in which—

Fig. 1 is a perspective view of a nail set constructed in accordance with my invention.

Fig. 2 is a perspective view of the opposite side of the nail set.

Fig. 3 is a sectional view through a flooring and through a nail set in functional position, and

Fig. 4 is a perspective view of a flooring and a nail set in functional position.

The floor is shown as consisting of base strips 1, having upstanding, dove-tailed ribs or keys 2, engaging complementary grooves 3 in the blocks 4. The blocks 4 and the base strips may be assembled in the factory as units and they will be of appropriate lengths so that they can be connected together to form a floor. The opposite edges of the blocks are provided with grooves 5 to receive key strips 6 so that tongue and groove connections are provided for the blocks on adjacent units. The blocks, or at least some of them in each unit, are provided with recesses 7 having approximately the same cross sectional area as the heads 8 of the nails 8 and the ends of the recesses 7 may be drilled or bored for a short distance to receive the nails 8 which may be driven into the blocks until they almost perforate them. In other words, the nails will be initially introduced

into the blocks until they assume the position indicated by the nail A in Fig. 3.

This is preferably done at the factory so that when the units are shipped, the nails will be in place. It will only be necessary then to align the units with adjacent units and connect them by the key strips 6 so that it will only be necessary for the operator to set the nails or drive them home. The nails are of sufficient lengths so that when they are set, they will be caused to penetrate the key strips 6 and be driven into blocks on an adjacent unit, as clearly seen in Fig. 3.

The nail set for accomplishing the setting of the nails is shown as consisting of a bar 9 provided at one end with a handle 10 and at the other end with a bolt-supporting head 11 transversely of the bar 9. The inner face of the head 11 is provided with a nail feeler or locator bar 12, having a concave portion 13 at one end to contact with the head of the nail. The concave portion 13 of the feeler rib or bar 12 integral with the head 11 is adjacent to an opening 14, through which projects a nail setting bolt 15, having a head 16 on its outer end against which one end of an expansion spring 17 bears, the other end of the spring bearing against the head 11, as at 18. The spring 17 will have a normal tendency to press the bolt outwardly, the outward movement being limited by the shoulder 19 on the bolt 15, as will be clearly seen in Fig. 3.

There is a guide sleeve 20 for the bolt, the sleeve being preferably integral with the head 11 and provided with a slot 21, in which may move a bolt holding brake or lever 22, pivoted intermediate its ends at 23 and having a projection 24 at its upper end, normally pressed outwardly by the spring 25, bearing against the projection and against the lug 26 on the bar 9. The lower end 27 of the brake or bolt-holding member 22 is adapted to contact with the bolt or set as it is driven inwardly to set the nail by the blows of a hammer so that when the initial blow is exerted against the head 16 and the nail is given its first impulse to penetrate the key strip, the brake 22 will hold it against being retracted so that it will be in a position under the impulse of additional blows to drive the nail into its final position.

When the operation has been accomplished, pressure may be applied to the projection 24, either manually or by tapping

it with a hammer, so that the brake end will be released from contact with the bolt and the spring 17 may force the bolt to its normal position.

5. It will be observed that the positioning or feeler bar or rib 12 is so disposed on the face of the head 11 that it may engage in the grooves 5 of the blocks. The floor of the groove in which the rib 12 is located will act 10 as a support for the set so that it can be slid along the groove with a minimum of effort. Since the heads of the nails initially project into the groove 5, the operator may stand on the floor and by grasping the handle 10, move the head along the groove until 15 the portion 13 contacts with the head. This will bring the head in longitudinal alignment with the bolt 15 so that the operator will know that the nail can be set by striking 20 on the head 16. Therefore, it will be apparent that the member 12 not only supports the head in the groove but it also locates the nail and positions the bolt in line therewith so that the nail can be driven through the 25 key strips and into a block on an adjacent unit.

By drilling the recess 7 and the smaller recess for the introduction of the nail, the nail will be guided in a straight line and liability 30 of its being deflected when it is being set will be eliminated.

It will be apparent that the operation of laying the floor may be expeditiously carried on without the aid of especially skilled 35 operators and that proper nailing of one unit to a complementary unit may be conveniently conducted.

What I claim and desire to secure by Letters-Patent is:

40. 1. A nail set comprising a bar having a

floor groove-engaging, nail-locating rib and a nail setting bolt carried by the bar and movable across the plane of the rib and having its end adjacent to one end of the rib.

2. A nail set comprising a bar having a 45 floor groove-engaging, nail-contacting rib, a bolt for setting the nail, and a friction device for holding the bolt into contact with the nail during the driving operation.

3. A nail set comprising a T-shaped bar 50 having a handle at one end, the head of the T being provided with a groove-engaging, nail-locating rib running lengthwise of the head and terminating at about the center thereof, a bolt-guiding means on the head, 55 and a spring-pressed, retracted bolt in the guiding means and movable through the head at right angles to the rib.

4. A nail set comprising a plate adapted to slide over the work and having an abutment to engage a projection, such as a partly driven nail, and a transversely slideable bolt aligned with said abutment and capable of playing past the same to drive such nail, the shape and proportions of the abutment being 60 such as to align the bolt with the nail.

5. A nail set comprising a plate adapted to be slid over the work and having an abutment to engage a projection, such as a partly driven nail, a spring-retracted, transversely 70 slideable bolt aligned with said abutment and capable of playing past the same to drive such nail, the shape and projections of the abutment being such as to align the bolt with the nail, and means for frictionally 75 engaging the bolt to temporarily hold it against retraction by the spring after it has moved into nail-driving position.

In testimony whereof I affix my signature.

CHARLES J. CARTER.
